UNITED STATES PATENT OFFICE.

WILLIAM F. HUDSON, OF PHILADELPHIA, PENNSYLVANIA.

DESIGN FOR A BASE FOR AN AMUSEMENT AND EXERCISING DEVICE.

Application filed April 28, 1923. Serial No. 5,997. Term of patent 14 years.

To all whom it may concern:

Be it known that I, WILLIAM F. HUDSON, a citizen of the United States, residing at Philadelphia, in the county of Philadelphia and State of Pennsylvania, have invented a new, original, and ornamental Design for a Base for an Amusement and Exercising Device, of which the following is a specification, reference being had to the accompanying drawings, forming part thereof, in which—

Fig. 1 is a perspective view of a base for an amusement and exercising device showing my new design as viewed from beneath, and

Fig. 2 is a similar view thereof as viewed from above.

I claim:

The ornamental design for a base for an amusement and exercising device substantially as shown.

WILLIAM F. HUDSON.
